(57) **CLAIM**

The ornamental design for a battery grip for a camera, as shown and described.

DESCRIPTION

FIG. 1 is a front view of the battery grip for a camera, showing our new design.

FIG. 2 is a rear view thereof.

FIG. 3 is a left side view thereof.

FIG. 4 is a right side view thereof.

FIG. 5 is a top view thereof; and,

FIG. 6 is a bottom view thereof.

Fine lines shown on surface parts of the respective drawings are lines that indicate the shape of a solid surface. The broken lines in the drawings depict portions of the battery grip for a camera that form no part of the claimed design.
